UNITED STATES PATENT OFFICE

FRANK P. C. DAVIS, OF KELSO, WASHINGTON, ASSIGNOR TO THE LAWRENCE PRODUCTS COMPANY, INCORPORATED, OF KELSO, WASHINGTON, A CORPORATION OF WASHINGTON

MEDICAL POWDER APPLICATOR

Application filed April 21, 1930. Serial No. 446,083.

The invention relates to a surgical device for spraying medical powder or other medicament in the treatment of cavities, passages and like parts, said device including inner and outer tubes having a telescopic arrangement, and a bulb connected by a flexible tube to the inner tube for expelling the powder when the instrument is in position for treating the affected parts.

10 While the drawings illustrate a preferred embodiment of the invention, it is to be understood that in adapting the means to meet specific needs and requirements, the design may be varied and changes in the minor details of construction may be resorted to within the scope of the invention as claimed without departing from the spirit thereof.

15 For a full understanding of the invention and the merits thereof, reference is to be had 20 to the following description and the drawings hereto attached, in which:

Figure 1 is a side view of a powder applicator embodying the invention, parts being broken away.

25 Figure 2 is a similar view, parts being broken away and the inner tube partially withdrawn.

Corresponding and like parts are referred to in the following description and designated in the several views of the drawings by like reference characters.

The device comprises an outer tube 1 having an end portion tapered as indicated at 2. An inner tube comprising a straight portion 3 and an oblique portion 4, is slidable within the outer tube 1. A washer 5 insures a close fit between the two tubes and may be of rubber or other suitable material. A bulb 6 is connected by means of a flexible tube 7 to the outer end of the inner tube and when compressed sends a blast of air through the inner tube and expels the contents thereof.

40 The outer tube functions as a sheath and, in practice, is introduced into the opening or cavity to be treated and receives and pro-

50 tects the inner tube which contains the powder or other medicament to be applied to the surface or walls of the passage or opening to be treated. A mark 8 is provided on the inner tube to indicate the amount of powder 55 to be used in a single treatment and after the inner tube has received a charge it is introduced into the outer tube and moved therein until its extremity touches the base of the tapered end 2 of the outer tube 1 and upon 60 compressing the bulb 6, the powder is discharged and applied to the walls or surface of the part to be treated.

65 The inner and outer tubes may be of glass, hard rubber, metal, or other determinate material and the lumen of the outer tube 1 is of a diameter to snugly receive the straight portion 3 of the inner tube which telescopes 70 therein. The device is aseptic and may be readily sterilized and prevents dropping of the powder when the inner tube is charged and the device is manipulated to properly position it for treatment of the affected parts.

Having thus described the invention, what is claimed is:

An aseptic medical powder applicator comprising a straight outer tube having its forward end portion tapered, a removable inner tube having a straight portion telescoping into the outer tube, the straight portion of the inner tube being of less diameter than the rear end of the tapered portion of the outer tube and of greater length than the outer tube whereby the inner tube may be slid freely through the outer tube and have its front end engaged with the walls of the tapered forward end portion of the outer tube to form a tight joint, a sleeve fitting snugly in the rear end of the outer tube and fitting closely about the inner tube to form a closed joint between the tubes and guide sliding movement of the inner tube, and a bulb connected to the rear end of the inner tube.

In testimony whereof I affix my signature.

FRANK P. C. DAVIS. [L. s.]
